FIG. 3

FIG. 4

J. Cohen

UNITED STATES PATENT OFFICE.

JAMES COHEN, OF NORTHAMPTON, MASSACHUSETTS.

ROLLER SKATE.

Application filed October 27, 1927. Serial No. 229,205.

This invention relates to roller skates and key carrying frame attachment therefor and it consists in the novel features hereinafter described and claimed.

5 An object of the invention is to provide in combination with a skate a frame adapted to be applied thereto and having means for securely retaining a key or wrench which is used upon the nuts and bolts of the skate when 10 it is desired to shift or adjust the parts thereof.

With this object in view the skate frame includes upper and nether plates one of which is provided with a bolt and the other 15 with a stud. Both of said plates are provided with slots which receive the bolt and stud. A frame is carried by the stud and bolt at the undersurface of the nether plate and said frame is provided at one end with a stud 20 and at its opposite end with a recess. The key or wrench is provided with a sleeve which is slidably mounted upon its handle and a spring is housed in the sleeve and interposed between the end of the key and a cross pin 25 carried by the sleeve and serves as means for normally holding the sleeve extended with relation to the handle of the key. The key is provided at its end with a lug and when the key is positioned within the frame the said 30 lug is received in the recess of the frame and the end of the sleeve receives the stud of the frame.

In the accompanying drawings:—

Figure 1 is a side elevational view of a 35 skate with the key frame and key applied;

Figure 2 is a perspective view of the key frame detached;

Figure 3 is an enlarged fragmentary longitudinal sectional view of the skate showing the key and key frame in elevation and parts 40 in section;

Figure 4 is a horizontal sectional view of the key frame and key showing the parts in engagement with each other;

Figure 5 is a similar view showing the key 45 disconnected from the ends of the key frame;

Figure 6 is a transverse sectional view of the key cut on the line 6—6 of Figure 3.

The skate includes an upper plate 1 adapted 50 to lie under the forward portion of the foot when the skate is applied and a nether plate 2 adapted to lie under the heel portion of the foot of the wearer. Said plates are provided with longitudinally disposed slots 3.

55 The plate 2 is provided with a bolt 4 which passes through the slot of the plate 1. The

plate 1 is provided with a rivet 5 which passes through the slot of the plate 2. A nut 6 is screwed upon the lower end of the bolt 4 and serves as means for securing a key frame 60 (hereinafter to be described) to the under side of the plate 2.

The key frame consists of a strip 7 bent in the general form of a loop and provided with openings 8 and 9 for the reception of the bolt 65 4 and the rivet 5 respectively. The frame 7 is provided at one end with a recess 10 and at its opposite end with an inwardly disposed stud 10'.

The key comprises a head 11 having at its 70 sides recesses 12 adapted to receive the nut 6 hereinbefore referred to. The head 11 is provided at its forward end with a lug 13 adapted to be received in the recess 10. The key is provided with a non-circular handle 14 75 which is integrally joined with the head and a sleeve 15 is slidably mounted upon said handle. The sleeve is provided at its opposite sides with slots 16 which receive a cross pin 17 carried by the handle 14. The 80 pin 17 is provided at one end with a lug 18 which is disposed opposite a lug 19 fixed upon the body of the sleeve. The lug 19 is attached to the sleeve by means of cross pins 20 and a spring 21 is housed within the sleeve 85 and bears at one end against the end of the handle 14 and at its other end against the pins 20. The spring 21 is under tension with a tendency to normally hold the sleeve at an extended position upon the handle 14. 90 The outer end of the sleeve 15 is open and is adapted to receive the stud 10'.

When the key is being carried by the skate the parts are in the positions as shown in Figures 1, 3 and 4 of the drawings. When the 95 key is removed from the skate the lugs 18 and 19 are grasped between the fingers and the lug 18 is moved to the position as shown in Figure 5 of the drawings whereby the spring 21 is compressed. This moves the sleeve 15 100 along the handle 14 and the lug 13 disengages the recess 10 and the end of the sleeve disengages the stud 10'.

I claim:—

1. A skate comprising a frame having overlapping plates provided with bolt and slot connecting means, a frame having an opening adapted to receive the bolt and adapted to be positioned at the under side of the nether plate, said frame being provided at one end 105 with a recess and at its opposite end with a stud and a key having a sleeve telescopically 110

mounted thereon, said key having a lug adapted to enter said recess and said sleeve adapted to engage said stud.

2. A skate comprising overlapping plates having a bolt and slot connection, a frame consisting of a strip of material having an opening adapted to receive the bolt, said frame being provided at one end with a recess and at its opposite end with a stud, a key 10 having a handle with a sleeve telescopically mounted thereon, a spring housed within the sleeve and bearing at one end against the sleeve and at the other end against the handle and serving to normally hold the sleeve at an 15 extended position with relation to the handle, said key having a lug adapted to enter said recess and the end of the sleeve adapted to receive said stud.

3. In combination with a frame adapted to be applied to a skate, a key having at its head a lug adapted to engage the frame, a sleeve slidably mounted upon the handle of the key and provided with slots at its sides, a pin carried by the handle and passing 25 through the slots of the sleeve, a lug mounted upon the sleeve, bolts passing through the slot and connected to said lug and a spring housed within the sleeve and bearing at one end against the handle and at its opposite 30 end against one of said bolts.

4. In a roller skate having a body connecting front and rear wheels, a pair of spaced depending members carried by and upon the under face of the body, a skate key designed 35 to be positioned between said members and

comprising two loosely connected parts, and a resilient element connected to said parts and normally urging the same apart for engagement with and support by the members.

5. In a roller skate having a body portion 40 connecting front and rear supporting wheels, spaced depending members carried by the body at the under side thereof, a skate key comprising a head portion and a telescoping two-part handle portion, resilient means normally acting to shift the two parts of said handle to increase the length thereof, and means associated with the opposing faces of said depending members whereby the head and free end of the handle of said wrench 45 may be removably connected therewith and held in position beneath the body through the action of said spring.

6. In a roller skate having a body connecting front and rear wheels, a supporting element consisting of a pair of depending members carried by and upon the under side of the body, a key element designed to be carried by the supporting element, and means whereby one or the elements may be adjusted for 50 locking engagement with the other element.

7. The combination with a roller skate, of a key support upon the under side of the skate body, and a key member designed to be adjusted for locking connection with the support, to be detachably carried thereby.

In testimony whereof I hereunto affix my signature.

JAMES COHEN.
